UNITED STATES PATENT OFFICE.

WILLIAM B. JARVIS, OF GRAND RAPIDS, MICHIGAN.

RADIATOR CAP.

Application filed June 18, 1926. Serial No. 116,870.

The main objects of this invention are:

First, to provide an improved radiator cap which is effectively sealed against the escape of water or steam and also one in which the ornamental features of the cap may be properly aligned or positioned relative to the radiator.

Second, to provide a cap having these advantages which is comparatively simple and economical in structure and is not likely to become inoperative for the purpose as a result of severe usage.

Objects pertaining to details and economies of my improvements will definitely appear from the detailed description to follow. The invention is clearly defined and pointed out in the claims.

A structure embodying the features of my invention is clearly illustrated in the accompanying drawing forming a part of this application, in which:

Fig. 1 is a fragmentary view partially in vertical central section through a radiator neck and cap embodying the features of my invention, the section being on a line corresponding to line 1—1 of Fig. 2.

Fig. 2 is a plan view of the thrust member.

Fig. 3 is a detail view on a line corresponding to the curved line 3—3 of Fig. 2.

Fig. 4 is a fragmentary section corresponding to that of Fig. 1 with the closure member omitted.

Referring to the drawing, 1 represents the threaded neck of an automobile radiator. In the embodiment shown in Fig. 1 the cap 2 is internally chambered and provided with ornamental projections 3 conventionally indicated. This cap has an internal annular stepped shoulder providing an annular seat 4 and an outer seat 5. The inner seat 4 constitutes a support for the tongue-like springs 6 of the annular thrust member 7, these springs being struck from the body of the thrust member and being of general segmental form loosely fitting in the recess formed by the inner step of the shoulder and resting on the seat thus provided.

The diameter of the thrust member 7 is such that it is loosely supported by the springs in the cap, the seat 5, however, constituting a stop limiting the collapsing of the springs. This prevents the complete collapsing of the springs and the possible consequent "setting" thereof.

The thrust member 7 urges the gasket 8

against the end of the neck 1 yieldingly supporting the gasket and also providing means for yieldingly holding the cap in its adjusted positions on the neck to properly present the ornamental features of the cap.

In the embodiment shown in Fig. 1 a closure 9 is provided, the edges of this closure being disposed between the thrust member and the gasket, thereby providing a sealing means at the top of the gasket so that steam or water cannot pass around the gasket and downwardly through the threads.

In the modification shown in Fig. 4 this feature is omitted.

For convenience in manufacture I provide the cap with an internal bushing 10 of brass or other suitable non-corrodible material to receive the threads, this bushing being cast or molded on to an annular rib 11 whereby the bushing is retained in place.

The cap has an opening 12 in the top adapted to receive the stem of an ornament or the like and this opening is closed by a removable disk 13 which may be punched out or removed to permit the attachment to be inserted and secured in the opening; or, if desired, the cap may be used without such ornament, the disk serving as an effective finish for the top of the cap.

With this arrangement of parts a substantially perfect seal is secured, that is, the water and steam cannot escape around the gasket when the closure 9 is present. Further, the gasket is relieved of the stresses which would be likely to destroy the same in the turning on and removal of the cap. The cap may be positioned as is proper to correctly present the ornamental features thereof.

By providing the stop limiting the collapsing of the spring members, the springs cannot be "set" or subjected to such pressure as is likely to destroy them.

Having thus described my invention what I claim as new and desire to secure by Letters Patent is:

1. The combination with a threaded neck, of a chambered internally threaded cap having an annular stepped downwardly facing shoulder, a gasket arranged to engage the end of the neck, and a thrust member for applying yielding pressure to said gasket and retaining the cap in its adjusted positions on said neck provided with a spring disposed to engage the inner step of said shoulder, the outer step of said shoulder con-

stituting a stop coacting with said thrust member limiting the collapsing of the spring.

2. The combination with a threaded neck, 5 of a chambered internally threaded cap having a downwardly facing annular thrust surface, an annular thrust member disposed against said thrust surface and provided with a plurality of integral springs, a gasket 10 disposed to engage the end of the neck, said thrust member constituting means for applying yielding pressure to the gasket and retaining the cap in its adjusted position on the neck, and a closure member disposed 15 within said cap to coact with the upper side of said gasket and urged against said gasket by said thrust member.

3. The combination with a threaded neck, 20 of a chambered internally threaded cap having a downwardly facing annular thrust surface, an annular thrust member disposed against said thrust surface and provided with a plurality of integral springs, and a gasket disposed to engage the end of the 25 neck, said thrust member constituting means for applying yielding pressure to the gasket and retaining the cap in its adjusted position on the neck.

4. The combination with a threaded neck, 30 of a chambered internally threaded cap having an annular stepped downwardly facing shoulder, a gasket arranged to engage the end of the neck, and an annular thrust member for applying yielding pressure to said

gasket and retaining the cap in its adjusted 35 positions on said neck provided with a plurality of spring tongues disposed to engage the inner step of said shoulder.

5. The combination with a threaded neck, 40 of a chambered internally threaded cap having an annular internal recess, a gasket arranged to engage the end of the neck, an annular thrust member for applying yielding pressure to said gasket, said thrust member being provided with a plurality of springs 45 engaging said annular recess, and a closure member disposed within said cap to coact with the upper side of said gasket and yielding supported by said thrust member.

6. The combination with a threaded neck, 50 of a chambered internally threaded cap having an annular stepped downwardly facing shoulder, a gasket arranged to engage the end of the neck, an annular thrust member for applying yielding pressure to said gasket and retaining the cap in its adjusted positions 55 on said neck provided with a plurality of springs disposed to engage the inner step of said shoulder, the outer step of said shoulder constituting a stop coacting with said thrust member limiting the collapsing of the springs, and a closure member disposed with its edge between said thrust member and gasket and constituting a sealing means at the top of the gasket.

In witness whereof I have hereunto set my hand.

WILLIAM B. JARVIS.
